George F. Andrews

By His Attorney

Cornelius C. Pillings

UNITED STATES PATENT OFFICE.

GEORGE F. ANDREWS, OF GREENVILLE, SOUTH CAROLINA.

ROLL CLEARER.

Application filed May 9, 1925. Serial No. 29,034.

To all whom it may concern:

Be it known that I, GEORGE F. ANDREWS, a citizen of the United States, and a resident of Greenville, county of Greenville, South Carolina, have invented certain new and useful Improvements in Roll Clearers, of which the following is a specification.

My present invention relates to an apparatus for clearing or removing lint from top 10 rolls for roving and spinning frames and similar apparatus in textile work and, more particularly to a device for keeping the ends of the rolls and the adjacent parts of the apparatus free from accumulations of lint and 15 thread.

In the formation or carding of thread or slivers of fibres, a length or sliver of fibres is drawn through a series of rollers arranged in pairs of contacting or adjacent rollers between which the sliver of fibres passes. A small amount of fibres is torn loose from the passing slivers or thread and collects on the rolls, or on one of them, in the form of 20 lint. This lint may be readily taken up and removed from the roll on which it is formed or carried, by means of a roller coated with a fibrous or other surface on which the lint adheres more firmly or tenaciously than to the surface of the drawing rolls. The lint 25 which works to the ends or over the edges of the rolls is not however, to be removed in this manner as it is out of the reach of the clearing roll surface.

An object of my present invention is to 30 provide a clearing apparatus for rolls of this type by which the edges and ends of the rolls may be freed of lint.

Another object of the invention is to provide a clearing roll having clearing means 35 projecting outwardly from the surface of the roll.

Further objects of the invention are to provide a clearing roll arrangement which will permit the rolls to be readily adjusted, 40 to provide clearing means or brushes to be readily mounted on or removed from the ends of the cleaning rolls, and to provide an improved means for supporting and guiding the rolls and clearer.

With these and other objects in view the invention comprises the apparatus described and set forth in the following specification and claims.

The various features of the invention are 45 illustrated in the accompanying drawings in which;

Fig. 1 is a front elevation of a number of rolls and clearing rolls embodying a form of the invention.

Fig. 2 is a section of the apparatus shown in Fig. 1 taken on the line 2—2 of Fig. 1.

Fig. 3 is a side view of a portion of the apparatus showing the manner of mounting the clearing rolls.

Fig. 4 is an enlarged view of a portion of the apparatus taken partly in section through the clearing rolls.

Fig. 5 is a side view of the clearing roll and a section of the adjacent rolls indicating the action of the clearing rolls, and,

Fig. 6 is a detail view of a device for mounting the clearing brushes on the clearing rolls.

In the present invention, the clearing rolls are provided with a covering or surface of material which will readily pick up lint and fibres from the surface of the rolls to be cleared or maintained free of lint and are also provided with means projecting outwardly adjacent the end surfaces of the rolls for picking up the lint deposited past the edges of the roll surface. For this purpose the clearing rolls are made of the same length as the rolls to be cleared and brushes are mounted on the ends of the clearer rolls so as to project radially outwardly and sweep the ends of the rolls to be cleared. The clearing rolls are preferably made of wood or some similar material and the brushes are mounted on the end surfaces of the rolls by means of clips attached to the rolls by means of screws or other suitable means. The clearing rolls are so mounted as to resiliently press against the surface of the rolls to be cleared and to give or yield outwardly as the lint accumulates on them or as the rolls being cleared move apart as larger or smaller slivers are sent through the rolls.

Referring more particularly to the accompanying drawings, the clearing rolls are illustrated as applied to clear the upper rolls of a set of drawing rolls comprising two leather covered upper rolls 10 and 12 and two fluted or corrugated metal rolls 14 and 16 immediately beneath and contacting with the surface of the leather rolls. In this arrangement the lint has a tendency to adhere to the leather surface in preference to the steel or metal surface of the lower rolls and it is therefore necessary to clear only the upper rolls. As indicated in the draw-

ings, the lower rollers 14 and 16 are mounted on or made integral with shafts 18 and 20 which extend the length of the machine or unit while the upper leather coated rollers 10 and 12 are arranged in smaller groups, or in pairs, on shorter shafts 22 and 24. The rollers 10 and 12 rest on and are supported by the rollers 14 and 16 and are kept in proper position by positioning the ends of the shafts 22 and 24 in notches or recesses 26 and 28 in guide members 30 between the ends of the shafts of adjacent groups. The guide members 30 are mounted by means of screws 32 or equivalent means, on swinging arms 34 pivoted and guided by a rock shaft 35 to permit the guides to rise and fall with the rolls 10 and 12.

Clearing rolls 36 embodying the present invention are supported and rest on the upper rolls 10 and 12, each clearing roll being supported, in the instance illustrated, on and by two of the upper rolls 10 and 12, the clearing rolls being mounted on and spaced along a shaft 38 which extends the length of the machine or unit of rolls. The shaft 38 is held in position at each end and pressed downwardly onto the rolls 10 and 12 by a half bearing 40 carried on a bracket 42 mounted on the guide members 30. The bracket 42 is provided with a horizontal slot 44 in its lower portion through which extends a bolt 46 mounted in an upstanding flange 48 on the guide member 30, in such manner that the bracket may be adjusted forwardly or rearwardly on the guide member and bolted in position to support the clearing roll on either or both upper rolls. On the upper portion of the bracket 42 is a guide socket for guiding the half bearing 40 formed by a trough 50 screwed onto the bracket at a slight angle to the vertical. The half bearing 40 is slidably mounted on the bracket by means of a stem 52 which extends into the guide socket formed by the trough 50 and is pressed downwardly against the shaft 38 by a spring 54 confined between the upper end of the stem and a pin 56 extending across the upper portion of the guideway. With this arrangement, the clearing rolls 36 are pressed resiliently downwardly onto the upper rolls 10 and 12 supporting and carrying the weight of the free end of the arm 34 and guide assembly 30—50, and the upper rolls and the clearing rolls are supported on the lower rolls 14 and 16.

The clearing rolls 36 are of approximately the same length as the rolls and are spaced approximately the same distance apart so that their ends are in alignment. The cylindrical surface of the rolls 36 is covered with a covering of felt or similar fabric 58 to which the lint adheres more tenaciously than to the leather surface of the rolls 10 and 12 so that the lint is picked

up from the rolls 10 and 12 and collected on the clearing roll 36 and thus kept away from the thread and the operating parts of the drawing rolls.

A portion of the lint, however, collects on the ends of the rolls 10 and 12 and is thus out of the reach and action of the cleaning surface of the cleaning rolls. To remove this accumulation of lint brushes 60 and 62 are mounted on the opposite ends of the clearing rolls 36 in such a manner as to project radially therefrom and sweep the end surfaces of the rolls 10 and 12 as the rolls rotate. These brushes are preferably removably mounted on the ends of the clearing rolls so that they may be removed and replaced when worn. For this purpose the holding end of the brush is clamped to the end of the rolls by means of a clip 64 secured to the roll end by a screw 66, which passes through an opening 68 in the face of the clip. The brushes are clamped under the clips and extend through notches 70 in the radially outward edges of the clips.

By means of the above invention the clearing rolls are so mounted on the drawing rolls as to ride freely thereon with sufficient pressure to pick up the loose fibres and lint without interfering with the action of the rolls. The portion of the roll assembly between the roll surfaces is moreover swept free of fibres and lint and maintained in a clear condition.

Having thus described my invention what I claim and desire to secure by Letters Patent is:

1. Apparatus of the type described which comprises, drawing rolls, clearing rolls mounted in fixed spaced relation to rotate on said drawing rolls, brushes on the ends of said clearing rolls and projecting radially therefrom, means secured to the end surfaces of said rolls for attaching the brushes to said end surfaces.

2. Apparatus of the type described which comprises, a series of drawing rolls mounted in spaced relation on a rotating shaft, clearing rolls mounted in fixed spaced relation to rotate on said drawing rolls, brushes on the ends of said clearing rolls and projecting radially therefrom and clips secured to the ends of said rolls for attaching said brushes thereto.

3. Apparatus of the type described which comprises, a lower roll, an upper roll supported and rolling on said lower roll, a cleaning roll supported on said upper roll, a guide for said upper roll resiliently supported from said clearing roll.

4. Apparatus of the type described which comprises, a lower roll, an upper roll supported and rolling on said lower roll, a clearing roll supported on said upper roll, a guide for said upper roll, a half bearing

receiving the upper thrust of said clearer roll and means for resiliently supporting said guide from said half bearing.

5. Apparatus of the type described which comprises, a lower roll, an upper roll supported on and rolling on said lower roll, a clearing roll supported on said upper roll, a rock shaft, a guide for said upper rolls pivoted to said rock shaft and supported 10 from said clearing rolls.

6. Apparatus of the type described which comprises, a lower roll, an upper roll supported on and rolling on said lower roll, a rock shaft, a guide for said upper rolls 15 attached to said rock shaft and a clearing roll rotatably supported on said upper roll and journaled in and supporting the free end of said guide.

7. Apparatus of the type described which 20 comprises, a lower roll, an upper roll supported on and rolling on said lower roll, a guide for said upper rolls, a bracket adjustably mounted on said guide, clearing rolls journaled to said bracket and resiliently supporting the weight of said guide.

8. Apparatus of the type described which comprises, a series of lower rolls mounted on a common axle, a series of upper rolls supported on and rolling on said lower rolls,

a series of guides for said upper rolls, 30 brackets on said guides, bearings mounted on said brackets, means for pressing said bearings downwardly relative to said bracket and clearing rolls mounted in said bearings and supported to roll on the upper 35 of said rolls.

9. Apparatus of the type described which comprises, a series of lower rolls mounted in spaced relation on a lower axle, a series of upper rolls similarly spaced and rolling 40 on said lower rolls, guides for said upper rolls, clearing rolls mounted to roll on and be supported on said upper rolls and means journaled on said clearing rolls and supporting said guides, and clearing brushes on 45 said clearing rolls projecting between said upper rolls.

10. Apparatus of the type described which comprises, lower rolls, a series of longitudinally spaced upper rolls supported and rolling on said lower rolls, guides for said upper rolls, clearing rolls supported on and rolling on said upper rolls, said clearing rolls having brushes at their edges projecting between said upper rolls, and means for 50 supporting said guides from said clearing rolls.

GEORGE F. ANDREWS.
